UNITED STATES PATENT OFFICE.

GODFRED T. ENGLUND, OF MIAMI, ARIZONA.

MEASURING ATTACHMENT FOR CAN-COVERS.

1,172,122.

Specification of Letters Patent. Patented Feb. 15, 1916.

Application filed February 25, 1915. Serial No. 10,506.

To all whom it may concern:

Be it known that I, GODFRED T. ENGLUND, a citizen of the United States, and a resident of Miami, in the county of Gila and State of Arizona, have invented a certain new and useful Improvement in Measuring Attachments for Can-Covers, of which the following is a specification.

This invention relates to an improvement in can closures, and more particularly contemplates the provision of a closure having a device whereby the contents of the can may be taken out in measured quantities as needed.

One of the principal objects of the invention is to provide a can closure with an extensible arm carrying a bowl, dipper, or spoon whereby measured quantities of the contents of the can may be taken out as needed, the arm being in the form of a pair of telescoping sections capable of being collapsed in order that the cover may be put in position on its can.

Another object of the invention is to provide such a device as I have set out, including an extensible arm hingedly connected to an expansion ring within the can top, the ring at its ends being provided with knobs or beads adapted to maintain the spoon or measuring device in the can top when not in use.

A still further object of the invention is to provide an improved attachment for can closures which will be extremely simple, durable, efficient in operation, and inexpensive to manufacture.

With these and other objects in view which will become apparent as the description proceeds, the invention resides in the construction, combination, and arrangement of parts, hereinafter more fully described and claimed and illustrated in the accompanying drawings in which like characters of reference indicate like parts throughout the several figures, of which—

Figure 1 represents a view in section taken centrally through the can and cover constructed according to my invention, the section being taken longitudinally of the measuring device, the latter being shown as collapsed and disposed within the cover. Fig. 2 represents a view in perspective of the cover, the measuring device being shown in extended position. Fig. 3 represents a bottom plan view of the cover, showing the device as collapsed and disposed therein. Fig.

4 represents a view in section taken transversely on the plane indicated by the line 4—4 of Fig. 2.

Referring more particularly to the drawings, a can such as a baking powder or soda can, is indicated at 5, and at 6 is indicated the cover or closure for the can. The cover is provided interiorly with an annular groove or channel at 7, preferably formed by stamping the metal of which the cover is made. Within this channel is adapted to rest a split expansion ring 8. The ends of the ring lie in spaced relation to each other and are beaded as at 9.

An extensible arm is provided and comprises an inner and an outer telescoping section 10 and 11 respectively. The section 10 has its edges overturned or flanged as at 12 to engage the edges of the section 11 in such manner that the latter section is slidably disposed upon section 10. The inner section or member 10 is longitudinally and centrally channeled as at 13, and member 11 is likewise provided with a central longitudinal channel 14 engaging within channel 13. This provides means whereby the sections may be relatively guided in their movements one with relation to the other.

The member 11 may be adjusted longitudinally of member 10, and will be maintained in adjusted position by the frictional engagement of the flanges 12 with said member 11. The latter at its outer end is provided with a dipper or spoon 15. The spoon may be formed integrally with member 11 or may be made separately therefrom and in some suitable manner attached to said member.

The inner end of member 10 is devoid of flanges 12, and is bent at right angles as at 16 and is then bent about the ring 8 as at 17, so that the member 10 is thus hingedly connected to said ring. The bent or beaded portion 17 lies within channel 7 and rotatably engages the split ring 8. The length of the right angularly bent portion 16 is substantially equal to the distance between the ring 8 and the outer edge, or rather, the free edge of the flanged portion 10 of cover 6, so as to allow of the extensible arm being swung outwardly at right angles to the flanged portion of the cover, and at the same time is adapted to bind against said flanged portion as shown in Fig. 2 so as to limit the outward movement of the arm when the latter attains its normal position.

At the point where the spoon joins the member 11, the latter is tapered or reduced as at 18, to a width slightly less than the distance between flanges 12, so that the 5 member 11 may be shifted inwardly to bring the spoon within the outer end of member 10.

When the device is not in use it may be collapsed and swung inwardly to be disposed within the can top in a manner indicated in Figs. 1 and 3. The point at which the extensible arm is connected with the ring is diametrically opposed to the split or break in the ring, so that as shown in 10 Fig. 3, when the spoon is folded inwardly its edges will engage the knobs 9 at the ends of the ring and will depress them sufficiently to allow the spoon to move beyond the ring, at which time the knobs will spring outwardly so as to maintain the spoon in position 15 within the cover. When it is desired to use some of the contents of the can, the cover is removed and the arm is engaged by the fingers and pulled outwardly so as to 20 detach the spoon from the retaining ring, and the arm 11 is then adjusted to the proper position relatively to arm 10. The spoon thus being in position indicated in 25 Fig. 2, may be utilized in dipping the desired quantity of the contents of the can.

Such a device as I have provided will be found to be of great convenience to housewives and cooks, for the reason that much valuable time will be saved, and many unnecessary steps in the search of proper measuring spoons will be avoided. The proportions and capacity of the bowl or spoon and the proportions of the extensible arm may of course be varied at the option of the manufacturer, to suit the requirements in various cases. When the cover is in place on its can, the attachment is completely housed and protected within the cover, so as to be out of the way.

40 Although I have described the preferred embodiment of my invention, I may desire to make such changes in the construction, combination, and arrangement of parts thereof as do not depart from the spirit of the invention and the scope of the appended claims.

I claim:—

1. A device of the class described comprising a can top having an annular channel 55 therein, a split expansible ring disposed within the channel and having its ends disposed in spaced relation and provided with beads, an extensible arm comprising a pair of members telescopically engaging each other, one of said members being provided with a measuring spoon the other member at one end being bent at right angles and looped over the ring at a point diametrically opposed to the ends of the ring; said arm 60 adapted to be moved inwardly whereby to

be housed within the cover, and adapted to be moved outwardly whereby to be used as a measuring instrument, and adapted to be adjusted longitudinally at will, said measuring spoon adapted to be engaged beneath the 70 beaded ends of the ring when folded inwardly, whereby to maintain said spoon within the cover.

2. A device of the class described comprising an extensible arm including an outer and an inner member, said inner member at its edges being provided with longitudinal overhanging flanges adapted to engage the outer edges of the outer member, said inner and outer members being provided with co-engaging longitudinal ribs, said outer member being provided at one end with a measuring spoon, the inner member being provided at one end with a right-angularly disposed portion, a can top, a ring disposed 80 within the can top, means on the right angularly disposed portion adapted to hingedly engage said ring, and means carried by the ring adapted to engage the measuring spoon when the latter is folded inwardly whereby 85 to maintain said spoon within the can top.

3. A device of the class described comprising a can top having a ring disposed therein, an extensible arm hingedly connected to the ring and adapted to be moved 90 outwardly to extend beyond the can top, a measuring instrument carried by the extensible arm, and means carried by the ring adapted to be engaged by the instrument whereby to maintain the latter within the 95 can top, substantially as described.

4. The combination with a can top, of an expansible ring disposed therein, an extensible arm provided at one end with a measuring implement and at its other end being hingedly connected to said ring, and means carried by the ring adapted to be engaged by the implement whereby to maintain the latter in housed position within the can cover 100 at will.

5. A device of the class described comprising a can top, an extensible arm, a measuring implement carried by said arm, the arm being adapted to be housed within the can top and being adapted to be swung outwardly 115 and extended whereby the implement may be used in dipping the contents of a can, means for hingedly connecting the extensible arm to the can top, and means whereby the 120 arm and implement may be maintained in housed position within the can top at will.

6. A device of the class described comprising a can top, a ring disposed therein, an arm hingedly connected with the ring, a measuring implement carried by the arm, and means connected with the ring for engaging the implement when the arm is 125 folded inwardly whereby to maintain the implement and arm within the top against accidental displacement.

7. The combination with a can top, of an arm, a measuring implement carried thereby, and means whereby the arm may be hingedly connected with the can top in such 5 manner as to fold within the same, said means being provided with a retaining means for maintaining the implement and

arm within the top against accidental displacement.

GODFRED T. ENGLUND.
